UNITED STATES PATENT OFFICE.

OTTMAR MERGENTHALER, OF BALTIMORE, MARYLAND, ASSIGNOR TO THE NATIONAL TYPOGRAPHIC COMPANY, OF WEST VIRGINIA.

LINOTYPE-MACHINE.

SPECIFICATION forming part of Letters Patent No. 558,406, dated April 14, 1896.

Application filed May 6, 1891. Serial No. 391,792. (No model.)

To all whom it may concern:

Be it known that I, OTTMAR MERGENTHALER, of Baltimore, State of Maryland, have invented certain Improvements in Linotype-
5 Machines, of which the following is a specification.

At the present day there are in extensive use machines known as "linotype-machines" for producing linotypes or type-bars, each bearing type characters to print a line. In these machines, represented in numerous Letters Patent heretofore granted to me, the linotype is cast from molten metal in a mold-cell, which is, for the time being, closed at the front by 10 a series of single-letter matrices assembled in the line side by side across the mold. The molten metal is delivered into the mold from the rear side through vents or orifices in the mouth of a melting-pot, which latter is seated 15 against and arranged to temporarily close the back of the mold. After the casting operation is performed the mouth of the pot is separated from the mold and the linotype therein, and the mold separated from the matrices 20 in order that the mold may be moved so as to bring the linotype in the path of an ejector, which, acting against the rear edge of the linotype, pushes the same forward out of the mold. In effecting the separation of the parts 25 30 after the casting operation there is sometimes a tendency of the linotype to adhere to the matrices and to draw forward partly out of the mold, so that it is liable to mutilation at the front and also carried out of the path of 35 the knife by which its base or rear edge is dressed. There is also a tendency at times for the base of the linotype to be so connected with the mouth of the melting-pot that when the latter retreats it will draw the linotype 40 backward out of the mold in an objectionable manner, so that it is liable to be unduly diminished in height by the trimming-knife.

Now it is the principal object of the present invention to secure the retention of the type-bar immovably in the mold until it has been 45 separated from the matrices at the front and from the melting-pot at the rear; and to this end it consists in slightly contracting the mold at the rear side, at the ends, so as to prevent 50 the linotype from passing backward.

Another feature of my invention consists in vents formed in the mouth of the melting-pot to permit the escape of the air from the mold.

It is to be understood that my improvements 55 may be applied to machines variously constructed as regards their details, but for the purpose of illustration I have shown the improvements in connection with a machine such as represented in Letters Patent of the 60 United States granted to me on the 16th of September, 1890, No. 436,532, to which reference may be had for the details of construction not found herein, the present drawings being limited to an illustration of those parts 65 to which my invention particularly relates.

In the accompanying drawings, Figure 1 is a vertical central section on the line 1 1 of Fig. 3 through the mold-wheel, the mouth of the melting-pot, and the line of matrices assembled in front of the mold, the parts being in position for casting. Fig. 2 is a similar view of the parts as they appear when separated after the casting action on the line 1 1 of Fig. 3. Fig. 3 is a horizontal section 75 on the line 3 3 of Fig. 2. Fig. 4 is a vertical section on the line 4 4 of Fig. 3. Fig. 5 is a face view of the mouth of the melting-pot, showing the construction of the surface which closes over and against the mold. Fig. 6 is a view of one of the matrices. Fig. 7 is a perspective view of the linotype in the form in which it is cast in the mold. Fig. 8 is a view of the finished linotype.

Referring to the drawings, A represents a 85 vertical mold-wheel having a mold cell or slot a cut therethrough from front to back, this cell having dimensions corresponding with that of the required linotype or type-bar B, such as shown in Fig. 8.

C represent a series of matrices, such as shown in Fig. 6, to be arranged temporarily in line across and against the face of the mold in order to expose their characters or matrices proper, c, in front of the mold-cell a. 90

D is a yoke or support by which the assembled or alined matrices are held in position in front of the mold.

E is the mouth or spout of a melting-pot having its flat vertical face adapted to fit 100

over and close the rear side of the mold-cell and having in said face a series of orifices e , opening into the rear side of the mold-cell. The pot is adapted, as heretofore, to contain 5 a large supply of molten metal and is provided with the customary heating appliances and with a pump or equivalent means for forcing the molten metal at the proper time through the orifices e into the mold-cell.

10 The mold-wheel is carried by a shaft a' , mounted in horizontal sliding bearings a^2 , in order that the wheel may move to and from the stationary line of matrices, and this for the purpose not only of insuring a close contact between the face of the mold and the 15 faces of the matrices, but also for the purpose of drawing the elevated characters of the linotype out of the cavities in the matrices, so that the mold-wheel may revolve without mutilating the characters. The melting-pot is also mounted as in my previous machine, so as to move horizontally to and from the rear face of the mold in order to effect the separation of the sprues or gates from 20 the rear edge of the linotype and to release the mold that it may revolve. After the casting of the linotype the mold-wheel revolves until the mold-cell and the linotype therein are carried past a stationary knife 25 F , which dresses off the rear edge of the linotype, and presented in front of a reciprocating ejector G , which drives the linotype forward out of the mold-wheel and between stationary guides H , which dress off its side 30 faces.

35 The foregoing parts are constructed and operate in essentially the same manner as in my previous machine, and are detailed herein simply to a better understanding of my improvements.

40 The first improvement consists in providing the face of the mold with one or more notches or overflows e^2 , such as shown in Figs. 3, 4, and 5, so that when the mouth of the 45 pot is fitted against and delivers metal into the mold the metal is permitted to slightly overflow the back of the mold, thereby forming on the rear edge of the projecting linotype lips b , such as shown in Fig. 7. These 50 lips resist any forward motion of the linotype within the mold, and when, therefore, the mold is retracted from the matrices the lips compel the linotype to move back with the mold and effect the separation of its front 55 edge from the matrices. This insures the leaving of the linotype in its original position in the mold.

60 The second improvement consists in forming the mold-cell, as shown in Fig. 3, with inwardly-projecting shoulders a^3 at its ends and at the rear face, or, in other words, in reducing the length of the mold-cell at the rear side, so that it is impossible for the linotype to be drawn backward out of the mold. The 65 shoulders a^3 , holding the linotype firmly against the backward strain, admit of the melting-pot being drawn back so as to rup-

ture or separate the sprues from the rear edge of the linotype without drawing the latter backward. The consequence is that the knife 70 F is prevented from cutting the linotype to less than its proper height.

75 In order to secure the production of sharp clean type characters, I find it advisable to project the inflowing metal directly toward and against the matrices at the opposite side of the mold. This may be effected, however, in such manner that the sprues or gates formed in the inlet-orifices may be readily separated from the pot. I therefore construct the inlet- 80 orifices in the mouth of the pot in the form shown in Figs. 1, 2, and 3. The rear portion of the orifice through which the metal leaves the mouth of the pot is of uniform diameter and in such position that the jet will be projected directly through the mold from the back to the front. The forward portion of each orifice is, however, counterbored or enlarged, as shown at e' , in conical or flaring form, with the larger end toward the mold, so 85 that the conical teats, sprues, or gates formed on the back of the linotype will adhere thereto and draw out of the orifices in the mouth of the pot. If the mouth of the pot is not counterbored, the sprues have a tendency to 90 draw back with the pot and pull the semi-molten metal out of the back edge of the linotype or slug, thus leaving the latter hollow and weak at its back face. The orifices may 95 be modified somewhat in form, provided they 100 retain the mode of action herein described, the essential feature being the enlargement of their forward or delivery ends, while the rear ends are adapted to deliver a small clearly-defined jet.

105 The last feature of my invention relates to the delivery of the contained air from the mold as it is displaced by the incoming metal. In order to secure a linotype which shall have sharp characters and a solid texture at the 110 front, it is important that a large portion of the air shall be permitted to escape from the mold, and that it shall escape in such manner as to prevent its imprisonment by the metal in the front of the mold. I therefore 115 provide in the face of the melting-pot, as shown in Figs. 3 and 5, small vents I , in the form of shallow grooves, commencing at the delivery-orifices and diminishing in depth 120 toward the side faces of the mouth.

125 In practice it is found that the air compressed by the inflowing metal at the front of the mold will be crowded backward and escape through the vents at the rear of the mold between its face and the face of the pot. The metal will sometimes enter these vents; but as they are very shallow and the fins consequently very thin the latter are immediately chilled and hardened, so that there is no appreciable leakage of the metal. These vents 130 may be modified somewhat in form; but the form shown in the drawings is found to be best adapted for ordinary use.

135 The contraction of the mold endwise at the

rear side gives a firm support to the slug, so that it will not be drawn backward by the sprues connecting it with the mouth of the pot when the latter retreats. The construction, however, permits the slug to be driven readily forward out of the mold and permits the use of an ejector-blade of a thickness substantially equal to that of the slug or linotype, so that there is no danger of the ejector embedding itself in the center of the slug, which is frequently porous and soft.

Having thus described my invention, what I claim is—

1. In a linotype-machine and in combination with a melting-pot separably therefrom, a solid mold having a flat rear surface and rectangular mold-slot, the latter contracted endwise at the rear corners only, whereby the withdrawal of the slug in a rearward direction is prevented and the use of an ejector of

substantially the same thickness as the slug is permitted.

2. In a linotype-machine, the combination of the mold adapted for the formation of a linotype, the melting-pot to close the rear 25 side of the mold, provided with one or more vents I.

3. In combination with the mold, the melting-pot having the delivery-orifice and a laterally-extending air-vent I, extending from 30 the orifice outward and of diminishing depth, as described.

In testimony whereof I hereunto set my hand this 24th day of March, 1891, in the presence of two attesting witnesses.

OTT. MERGENTHALER.
